UNITED STATES PATENT OFFICE

PASCAL SBURLINO, OF DAYTON, OHIO, ASSIGNOR TO THE NATIONAL CASH REGISTER COMPANY, OF DAYTON, OHIO, A CORPORATION OF MARYLAND

CASH REGISTER

Application filed July 23, 1928. Serial No. 284,645.

This invention relates to cash registers and like machines, and is more particularly directed to safety devices for preventing manipulation of such machines. As such it constitutes an improvement upon the safety mechanism disclosed in U. S. Letters Patent No. 1,763,915 issued to Edward J. Von Pein, on June 17, 1930.

The invention is shown applied to a machine of the general type disclosed in Letters Patent of the United States, No. 497,860, granted to Thomas Carney on May 23, 1893.

Machines of this type are equipped with one or more totalizers, adapted to be manually reset to zero. To prevent manipulation, access to the totalizers is normally prevented by a suitably locked lid.

To the totalizer disclosed in the patent to Carney, has been added a group of printing wheels, with manually operated means for taking an impression therefrom, as shown in the application of Von Pein above referred to.

Access to the totalizer for the purpose of printing the amount registered thereon, is obtained by unlocking and raising the lid, which heretofore controlled safety devices to prevent actuation of the accessible and movable parts, as the keys, while the lid was in its raised position. However, it has been found that, under certain circumstances, with the lid partly raised, it was possible for unscrupulous clerks to improperly manipulate the totalizer to cause it to register an incorrect amount.

In order to provide improved safety conditions which will render impossible such manipulation through improper operation of the keys while the lid is raised, the present invention has for its main object the inclusion in a cash register of the type disclosed by Carney, of a novel and improved safety device which locks the totalizer wheels against movement from the time when the operator starts raising the lid until the time when it is practically closed.

Another object is to provide a novel and improved interlock which prevents depression of a key and consequently operation of the machine while the lid is raised.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

Of said drawings:

Fig. 1 is a sectional view through the machine, showing the totalizer, the operating means therefor, and the means for taking the impression therefrom.

Fig. 2 is a detail view, illustrating particularly the manner of actuating the drive shaft.

Fig. 3 is a detail view of the lid and the interlock between the lid and the drive shaft, and between the lid and the totalizer.

Fig. 4 is a fragmentary view of one of the totalizer wheels and the locking arm therefor.

General description

The machine disclosed by Carney, which is only generally illustrated in the present application, includes a plurality of groups of keys and a totalizer for accumulating the amounts registered thereon by said keys.

Depression of the keys directly operates the actuating mechanism for the totalizer. This actuating mechanism is substantially the same as that disclosed in the above mentioned Carney patent.

A type wheel is conveniently connected to each totalizer wheel for recording the total. A manually operated impression hammer coacts with the type wheels, by which an impression can be made on record material.

Detail description

The keys 40 (Fig. 1) of each denominational group are pivoted on a common shaft 41, extending between side frames 42 and 43, (Figs. 1, 2 and 3) of the machine, and when any key is depressed, it raises a suitably graduated thrust link or actuator controller 44. The thrust link 44, as it rises, causes its graduated recess 45 to embrace a rod 46 carried by a yoke 47 pivoted on a shaft

48 extending between the side frames of the machine, and rocks said yoke clockwise a distance corresponding to the value of the key depressed, determined by the distance between the bottom of the graduated recess 45 and the rod 46 when the parts are in their normal positions. A toothed segment 49 fast on the yoke 47 actuates its associated totalizer wheel pinion 64 when the latter is engaged with its segment. There is a yoke 47 and a segment 49 for each denominational group of keys.

Depression of a key 40 (Fig. 2) also rocks a weighted key coupler 50 pivoted on trunnions 51 (Fig. 1) and 52 (Fig. 2) in the side frames 42 and 43, respectively. The clockwise movement of the key coupler 50 (Fig. 2) lifts a bifurcated rotation rack bar 53 connected thereto by a pin and slot connection 39. The bifurcated rack bar embraces a rotation shaft 56. Teeth 54 formed on one inner wall of the bifurcation in the rack bar 53 normally mesh with a gear 55 pinned on the rotation shaft 56 journaled in the side frames, and rotates the shaft in a clockwise direction, as viewed in Fig. 2 (counter-clockwise in Fig. 1).

A spring-pressed arm 57 (Fig. 2) has an inclined face 38 lying in the path of the rack bar 53. Depression of a key 40 rocks the key coupler 50 in clockwise direction (Fig. 2) to elevate the rotation rack bar 53, and as the bar rises, it contacts the inclined face 38 of the spring-pressed arm 57 and forces it aside. A lug 37 on the bar contacts a guide rail 36 fast to the side frame 43, to retain the rack bar in its rectilinear path of travel against the tension exerted laterally against the rack bar by the spring-pressed arm 57.

As the rack bar 53 arrives at its upper limit of travel, the lug 37 escapes the guide rail 36, whereupon the spring-pressed shifting arm 57 rocks the rack bar to disengage the teeth 54 thereof from the gear 55 and engage opposed rack teeth 58 formed on the opposite inner wall of the bifurcation, with the gear 55.

At this time, the pressure applied to the key 40 is relieved, whereupon the weight of the key coupler 50 lowers the rack bar 53 and continues the clockwise rotation of the rotation shaft 56 (Fig. 2) by the rack teeth 58, which now mesh with the gear 55. As the rack bar 53 arrives at its normal or starting position, a spring 59 (Fig. 2) rocks the rack bar 53 to re-engage the teeth 54 with the gear 55, preparatory to the next operation of the machine.

As the key 40 at the beginning of its depression, starts to rotate the shaft 56, a cam 60 (Fig. 1) pinned to the shaft, rocks a forked lever 61, pivoted intermediate its ends at 35 on a totalizer frame 62. The forward end of the lever 61 abuts against a stud 63 in the totalizer supporting frame 62 and rocks

the frame clockwise to engage the totalizer pinions 64 with their respective segments 49, so that when the segments are actuated, as above described, an amount equal to the values of the keys depressed, will be accumulated on the totalizer. 70

The rotation shaft 56 with its cam 60 thus controls the engagement of the totalizer pinions 64 with the adding segments 49 and their disengagement therefrom, the totalizer pinions normally lying out of engagement with the segments, and being rocked into engagement therewith at the beginning of the down stroke of a key 40. 75

It may be mentioned here that the nose of a spring-pressed pawl 96 (Fig. 2) pivoted at 104 on the frame 43, coacts with the toothed periphery of a disk 97 pinned to the rotation shaft 56 and constitutes a full-stroke device to insure that the keys 40 shall be fully depressed and restored, the mechanism preventing retrograde movement of the shaft 56, and hence of the key 40 connected thereto through the key coupler 50, rotation rack 53 and gear 55 in well-known manner. 90

The totalizer pinions 64 are individually journaled on a totalizer shaft 65 carried by the totalizer supporting frame 62. Gears 66, fast to their respective totalizer pinions 64, mesh with corresponding gears 67 on a shaft 68, also carried by the totalizer frame 62. A type wheel 69 and a reading wheel (not shown herein) are fast to each gear 67 and rotate therewith. The denominational adding segments 49, through this train of gears, accumulate various amounts, entered in the machine by the keys 40, on the type wheels 69 and on the reading wheels. 100

To print totals and sub-totals of the amounts registered on the totalizer, a record material is inserted in a suitable chute 76 (Fig. 1) extending forwardly over the printing wheels 69 from a cross rod 78 to which the rear end of the chute is conveniently pivoted, or the record material may be drawn through the chute from a supply (not shown) within the machine. A hammer 77 likewise pivoted on the rod 78 overlies the record material in the chute and carries a platen 79. By imparting a sharp blow to the hammer, the platen drives the record material through an opening (not shown) in the chute against the uppermost types on the type wheels 69 to impress the amount on the record material, the impression being inked in any suitable manner (not shown). 110

The printing mechanism forms no part of the present invention and need not be more fully described, a complete disclosure thereof being made in the Von Pein Patent No. 1,763,915, above referred to. 115

The totalizer may be reset to zero by the common expedient of manually turning the totalizer shaft 68 in any convenient manner (not shown) through one complete rotation 130

in the direction in which the wheels 69 are rotated in accumulating amounts. This may be done by the provision of an opening in the side of the cabin, through which a key may be inserted. A longitudinal groove in the shaft 68 when the latter is rotated, picks up spring-pressed pawls 99 pivoted to the respective wheels 69 to advance the totalizer wheels to their zero positions.

10 A shield 70 cooperates with the side frames 42 and 43 of the machine to enclose the working parts with the exception of the printing hammer and record material chute, the shield being apertured opposite the reading wheels 15 to permit reading the amount registered on the totalizer, and the entire machine is enclosed within a cabinet 71 to prevent access by unauthorized persons to the printing mechanism, as well as preventing the insertion of wires or other tools through the reading apertures in the shield 70 or around or through the printing mechanism for the purpose of mismanipulation.

Indeed when the cabinet is in place, the 25 only accessible parts are the forward ends of the key levers 40 which project through slots in the cabinet in a wellknown manner, not shown.

But it is necessary to afford a means of 30 access to the interior of the machine through the cabinet 71 to permit operation of the printing mechanism, to which end, it is customary to provide an opening in the cabinet above the printing mechanism and the totalizer, which opening is normally closed by a 35 lid 80 hinged to the cabinet, and locked against opening.

In general the key which unlocks the lid 80 is retained by the proprietor, but in many 40 cases, as when two or more clerks on different shifts use the machine it is desirable to permit each clerk to have access to the printing mechanism to enable him to make a record of the total amount of sales made by him 45 while on duty, as a check for his own protection, as well as to apprise the proprietor of the volume of business done during the various shifts.

Access to the interior of the machine, however, if no safeguards were provided, would 50 enable a dishonest employee to mismanipulate the record, and it has been customary, as disclosed in the Von Pein patent referred to, to provide means tending to prevent such 55 mismanipulation by one who has access to the printing mechanism.

The present invention is designed as an improvement on the mechanism shown in the Von Pein patent to render it even more difficult if not impossible to improperly manipulate or change the setting of the parts upon opening the lid, either accidentally or intentionally, and to this end, novel and improved means is provided which becomes effective as the operator starts to raise the lid

80, to positively lock the totalizer wheels against rotation by any means, and to positively prevent rotation of the drive shaft 56, and therethrough, lock the keys 40 against depression.

The improved mechanism includes a link 81 (Fig. 3), pivoted at its upper end to a bracket 82 depending from the inner face of the lid 80, the opposite end of the link having a longitudinally extending slot 87 formed therein, with closed ends, to accommodate a pin 86 projecting eccentrically from an arm 83 fast on one end of a cross shaft 84 journaled in the respective side frames 42 and 43 of the machine adjacent to and parallel with the totalizer shaft 65.

Detents 100 fast on the cross shaft 84 lie opposite ratchet wheels 88 fast with the respective totalizer gears 66 on the totalizer shaft 65, and a spring 85 individual to the arm 83 tends to rock the arm counter-clockwise (Fig. 3) and with it the cross shaft 84 and detents 100 to engage the detents with their respective ratchets 88 and lock the totalizer wheels 66 against rotation in one direction.

The weight of the lid 80, however, when in closed position, operates through the link 81 and stud 86 to hold the arm 83 normally at the limit of its clockwise travel, and thus retain the detents 100 withdrawn from engagement with the locking ratchets 88.

A second link 89 pivoted at one end at 99 to the arm 83 is provided with an open ended slot 102 at its opposite end to embrace a stud 90 carried by a pawl 91 pivoted at 103 to the adjacent side frame 42. A spring 92 individual to the pawl 91 tends to draw the nose 93 of the pawl towards a ratchet wheel 95 fast to that end of the rotation shaft 56 which passes through the side frame 42 to the outside thereof. With the parts at rest in their home positions, the ratchet wheel 95 is positioned so as to bring a recess 94 opposite the path of the nose 93 of pawl 91.

The weight of the lid 80, when closed, acting through link 81 and arm 83 as heretofore explained, operates to hold the second-named link 89 at the leftward end of its path of travel (Fig. 3), the closed end of the slot 102 in the link 89 bearing against the stud 90 on the pawl 91 to hold the latter disengaged from the locking ratchet 95, thus freeing the rotation shaft 56 to the action of the keys 40.

Thus it will be seen that so long as the lid 80 remains closed, the totalizer locking detents 100 and the rotation shaft locking pawl 91 remain in their idle positions.

Assuming, however, that the keys 40 being in their normal positions, the lid 80 is opened or raised.

At the very start, the lid 80 carrying the bracket 82, draws therewith the slotted link 81, to relieve the stud 86 and arm 83 of the weight of the lid, whereupon the individually operable spring 85 rocks the arm 83 counter-

clockwise to cause the stud 86 to follow up the inner end wall of the slot 87 in link 81 until a stop 105 arrests the arm at the end of its counter-clockwise path of movement.

5 Since the control arm 83 is fast on the cross-shaft 84, the latter and its detents 100 turn with the arm 83 until the noses of the detents engage the ratchets 88 fast on their respective totalizer wheels to lock the latter 10 against rotation.

Owing to the arrangement and operation of the parts, the totalizer wheels are locked before the lid 80 is raised sufficiently to enable the insertion of a tool by which to mismanipulate 15 the totalizer wheels, which are at all times held against reverse rotation by the usual locking detent pawls 106 (Fig. 1).

The control arm 83 on its counter-clockwise rotation under the influence of the spring 20 85 individual to the arm, draws the link 89 to the right (Fig. 3), thereby freeing the pawl 91 to the action of its spring 92, which rocks the pawl counter-clockwise to bring the nose 93 thereof opposite the abrupt side 25 wall of the recess 94 in the locking ratchet 95 on the rotation shaft 56.

The pawl 91, when in its effective position, locks the rotation shaft 56, the rotation rack 30 53 (Fig. 2), the key coupler 50, and the keys 40 against effective operation, so that after the operator starts to raise the lid 80, any attempt to depress a key 40 will be frustrated, as will any attempt to restore the totalizers to 35 zero, so that the only thing that can be done is to print the accumulated amount.

The longitudinal slot 87 in the link 81 permits the lid 80 to be swung to its fully open position, the outer closed end of the slot bringing up against the stud 86 to prevent 40 the lid from swinging too far back.

The lid 80 on being restored to its closed position, first lowers the link 81 relatively to the control arm 83, which latter remains at its farthest counter-clockwise limit of travel 45 100 with the detents 100 engaged with the ratchets 88 on the totalizer wheels, until just as the lid is about to arrive in its closed position, the inner closed end of the slot strikes the pin 86, and as the lid closes, the link 81 50 operating on the eccentrically located pin 86, rocks the control arm 83 to its farthest clockwise limit of travel, to rotate the cross shaft 84 similarly and withdraw the detents 100 from engagement with the totalizer ratchets 55 88.

The control arm 83 in rocking clockwise, thrusts the link 89 to the left (Fig. 3) to disengage the pawl 91 from the ratchet 95 on the rotation shaft 56.

60 Assume that the operator through mistake or intention partially depresses a key 40 before lifting the lid 80 in the first instance.

The key, when depressed, rocks the key coupler 50 clockwise (Fig. 2) and raises the rotation rack bar 53 partway to partially

turn the rotation shaft 56. Removal of pressure on the key 40 prior to the completion of its down stroke, will cause the full-stroke pawl 96 by engagement with the full-stroke ratchet 97, to lock the rotation shaft 56, and hence the locking ratchet 95 (Fig. 3) on the end thereof against reverse rotation. Hence, the totalizer pinions 64 (Fig. 1) are locked in mesh with their adding segments 49 with the parts in the positions which they occupied at 75 the time when the partially depressed key was relieved of pressure, and the key is held in such position against restoration.

If, at this time, the operator lifts the lid, the withdrawal of the link 81 as above explained, will free the control arm 83 to the action of its individual spring 85 which will immediately rock the control arm, its shaft 84 and the detents 100 in counter-clockwise direction to lock the totalizer wheels against 80 rotation in one direction, the usual detents 106 positively locking the totalizer wheels against rotation in the opposite direction.

The control arm 83 in its counter-clockwise travel draws with it the link 89, to free the pawl 91 to the action of its spring 92 which rocks the pawl counter-clockwise to engage the pawl with its locking ratchet 95. The partial turning of the rotation shaft 56 under the action of the partly depressed key 40 has 90 rotated the locking ratchet 95 to such an extent as to displace the deep notch 94 from the path of the locking pawl 91, so that the nose of the pawl engages one of the ratchet teeth on the periphery of the ratchet early in 100 its operation, and hence is not permitted the travel it would have if it entered the notch 94, but owing to the loose or variable sliding connection provided by the stud and slot 90 and 102 between the link 89 and the pawl 91, the early arrest of the pawl by its engagement with the locking ratchet 95 has no effect 105 on the effective operation of the detents 100, and the totalizer gears 64 will be locked whether or not an amount key 40 has been 110 partially depressed.

It is apparent from Fig. 4 that with the detents 100 in engagement with the ratchets 88, the gears 66 to which said ratchets are fixed, cannot be rotated clockwise, and therefore, the gears 67 to which type wheels 69 are secured, are locked against counter-clockwise movement.

From the foregoing it will be noted that the provision of the slidable connection between the totalizer lock, and the rotation shaft lock together with the provision of the springs 85 and 92, respectively, individual to the above-named locks, makes it possible for the totalizer lock to become effective at 120 a constant point in the operation of opening the lid, irrespective of the time of effective operation of the rotation shaft lock, the arrest of which by its contact with the teeth of the ratchet 95 merely operates to arrest 125

the stud 90 while the link 89 drawn to the right by the control arm 88 continues its travel.

As a result, the operator is still unable to mismanipulate the totalizer wheels after gaining access to the printing mechanism.

Restoration of the lid 80 to its closed position, operates as heretofore explained to withdraw the totalizer and rotation-shaft locks, allowing the totalizer to be returned to zero.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

20 What is claimed is:

1. In a machine of the class described, the combination with a totalizer; actuators for the totalizer; a drive shaft; manipulative means to operate the actuators and the shaft; 25 and a shiftable closure to normally prevent access to the totalizer; of safeguards to prevent mismanipulation of the totalizer, when the closure is opened, including normally idle means to lock the totalizer, and normally idle means to lock the drive shaft; and a device, including a plurality of sliding connections, one connection being intermediate the closure and the locking means for the totalizer, and another connection intermediate said one connection and the locking means for the drive shaft, all connections operable under control of the closure to enable the means for locking the totalizer to become effective irrespective of the means 30 for locking the drive shaft.

2. In a machine of the class described, the combination with a totalizer; actuators for the totalizer; a drive shaft; manipulative means to operate the actuators and the shaft; 45 and a shiftable closure to normally prevent access to the totalizer; of safeguards to prevent mismanipulation of the totalizer, when the closure is opened, including normally idle means adapted to receive a fixed extent 50 of movement to lock the totalizer, and normally idle means adapted to receive variable extents of movements to lock the drive shaft; a connection between the means for locking the totalizer and the means for locking the 55 drive shaft, said connection constructed to compensate for the variable movements of the drive shaft locking means; and means under control of the closure to determine whether the locking means shall be effective or ineffective.

3. In a machine of the class described, the combination with a totalizer; actuators for the totalizer; a drive shaft; manipulative means to operate the actuators and the shaft; 55 and a shiftable closure to normally prevent

access to the totalizer; of safeguards to prevent mismanipulation of the totalizer, when the closure is opened, including normally idle means to lock the totalizer, and normally idle means to lock the drive shaft; a loose 70 connection between the means for locking the totalizer and the means for locking the drive shaft; separate means to shift the respective locking means to their effective position; and means under control of the closure 75 to determine whether the locking means shall be effective or ineffective.

4. In a machine of the class described, the combination with a totalizer; actuators therefor; a drive shaft; manipulative means to operate the actuators and the shaft; and a shiftable closure to normally prevent access to the totalizer; of detents shiftable into and out of engagement with the totalizer, said shift being always the same extent; a normally idle and variably movable locking means for the drive shaft; a slideable connection between the detents and the locking means constructed to compensate for the variable movement of the drive shaft locking means; means tending to shift the detents and the locking means to their effective positions; and means controlled by the closure to determine whether or not the detents and locking means 85 shall become effective or ineffective. 90

5. In a machine of the class described, the combination with a totalizer; actuators therefor; a drive shaft; manipulative means to operate the actuators and the shaft; and a shiftable closure to normally prevent access to the totalizer; of a shaft journaled adjacent to the totalizer; detents mounted on the shaft to engage with and withdraw from the totalizer; a control arm on the shaft; a ratchet wheel on the drive shaft; a pawl to engage with and disengage from the ratchet; separate means to actuate the detents and the pawl; a connection between the control arm and the pawl constructed to permit relative movement between the detents and the pawl; and a pin and slot connection between the control arm and the closure. 100 105 110

6. In a machine of the class described, the combination with a totalizer; actuators therefor; a drive shaft; manipulative means to operate the actuators and the shaft; and a shiftable closure to normally prevent access to the totalizer; of detents shiftable into and out of engagement with the totalizer; a normally idle locking means for the drive shaft; a variable sliding connection between the detents and the locking means, including a control arm, and a slotted connection between the control arm and the locking means for the drive shaft; separate means operable upon the detents and the locking means to render them effective; and a loose connection between the control arm and the closure to hold the detents and locking means ineffective so long as the closure remains shut. 115 120 125 130

7. In a machine of the class described, the combination with a totalizer; actuators therefore; a drive shaft; a toothed disk thereon; manipulative means to operate the actuators
5 and the shaft; and a shiftable closure to normally prevent access to the totalizer; of detents shiftable into and out of engagement with the totalizer; locking means shiftable into and out of engagement with the toothed
10 disk; yieldable means to shift the detents and locking means in one direction to lock the totalizer and the shaft, upon movement of the closure to render the totalizer accessible; means actuated by the closure, upon
15 movement thereof to render the totalizer inaccessible, to positively shift the detents in another direction to unlock the totalizer; and means intermediate the detents and the locking means to positively shift the latter to unlock the shaft upon positive operation of the
20 detents.

In testimony whereof I affix my signature.
